BY Carl P. Jaepel

ATTORNEY

UNITED STATES PATENT OFFICE.

JULIEN STRANDERS, OF BROOKLYN, NEW YORK, ASSIGNOR TO HARRY B. KRUGER, OF NEW YORK, N. Y.

ADVERTISING DISPLAY DEVICE.

1,332,695.

Specification of Letters Patent.

Patented Mar. 2, 1920.

Application filed December 6, 1916. Serial No. 135,431.

To all whom it may concern:

Be it known that I, JULIEN STRANDERS, a subject of the King of Great Britain, and a resident of the borough of Brooklyn, in the 5 county of Kings, city and State of New York, have invented certain new and useful Improvements in Advertising Display Devices, of which the following is a specification.

- 10 The present invention relates to improvements in advertising display devices, and particularly display devices in the nature of show cards to be set up in connection with the goods to be displayed.
- 15 An object of the invention is to provide such a device which may be set up in such relation to, and supported by the goods to be advertised, as to provide for the goods an effective setting, and combining the goods and
- 20 display device in such an attractive and conventional manner as to readily attract interest and attention thereto. Another object is to produce such a device from a single piece of cardboard, or other suitable material,
- 25 making its production comparatively economical, and which when not set up into display position, will be flat, thereby facilitating shipping and protecting the same against damage.
- 30 With these and other objects in view, an embodiment of my invention is shown in the accompanying drawings, and this embodiment will be hereinafter more fully described with reference thereto, and the invention will be finally pointed out in the claims.

In the accompanying drawings,

Figure 1 is a perspective view of an embodiment of my invention, showing the same 40 set up in display position,

Fig. 2 is a plan view of the device in its flattened position for storing or shipping,

Fig. 3 is a side view of the same set up, and

Fig. 4 is a front view thereof.

Similar reference characters indicate corresponding parts throughout the several figures of the drawings.

Referring to the drawings, a practical embodiment of my improved display device comprises a main display portion 10 having the general shape of an inverted isosceles triangle. The upper portion may be of any suitable contour, thus for instance, 55 the corners may be cut as at 11 and 12, or

the same may have a shape to conform to the design of the advertising matter printed thereon. At each side of the lower part of the portion 10 there are provided triangular supporting or strut portions 13 and 14, and at the lower edges of the said strut portions, there are provided extensions or base portions 15 and 16 respectively.

Score lines 17 and 18 are provided between the main portion 10 and the strut 60 portions, and score lines 19 and 20 are provided between the strut portions and the base portions 15 and 16. The ends of the base portions are preferably shaped as at 21 and 22 to conform to the outline of the 65 articles to be displayed, to further enhance the attractive appearance of the device.

In setting up the device the portions 13 and 14 are turned back from the main portions so that their lower edges contact, 70 and the base portions are bent up into flat position so that they extend outwardly from the sides of the strut portions, whereupon the articles 23 and 24 to be displayed are placed upon the said base portions, and 75 against the sides of the main portion, thereby supporting the main portion in upright position. The main portion, it will be noted, assumes an inclined position in set up position, but this, it will be understood may be 80 varied as desired by changing the direction of the score lines 21 and 22 with relation to the junction between the main portion and the portions 13 and 14. It is not essential that the main portion 10 extend entirely to 85 the base portions.

I have illustrated and described a preferred and satisfactory embodiment of my invention, but it will be obvious that changes may be made therein within the 90 spirit and scope thereof, as defined in the appended claims.

I claim:

1. An improved display device comprising a panel all parts of which are disposed 100 in a common plane and having portions hingedly connected to one of its ends and adapted to be extended laterally therefrom in opposite directions and in parallel relation to and in contact with a supporting 105 surface, said panel adapted for arrangement with the articles to be displayed at each side of the panel in contact therewith and disposed upon said hinged portions to thereby maintain the panel in an erect position. 110

2. An improved display device, comprising an upright main display portion supporting portions hingedly connected to said main display portion, extensions hingedly connected to the lowermost edge of said supporting portions, and constituting base portions adapted to extend laterally from said supporting portion with their under surfaces in engagement with the supporting 10 surface for said device.

3. A display device comprising a main display portion, laterally disposed base means upon which the goods are adapted to be placed, and supporting means disposed 15 between said base means and said main display portion, the engagement of the goods on the said base means serving to fix the position of said base means to thereby main-

tain said supporting means in position to support said main display portion. 20

4. A display device, comprising a main display portion, supporting portions hingedly connected to said main portion at each side thereof, and base portions hingedly connected to said supporting portions and upon 25 which the goods are adapted to be placed to maintain said main display portion in erect position.

In testimony, that I claim the foregoing as my invention, I have signed my name in 30 presence of two subscribing witnesses.

JULIEN STRANDERS.
